[57] CLAIM

The ornamental design for an electronics tower
containing audio-visual electronics used in producing cus-
tomized video recordings, as shown and described.

DESCRIPTION

FIG. 1 is a perspective view of an electronics tower
showing my new design;

FIG. 2 is a front elevational view thereof;

FIG. 3 is a right side elevational view as seen when in
use, the rear view being identical thereto;

FIG. 4 is a left side elevational view as seen when in use;
and,

FIG. 5 is a top plan view thereof.

FIGS. 2 through 5 have been drawn on an enlarged
scale in respect to FIG. 1.

Fig. 1.

Fig. 2.

Fig. 3.

Fig. 4.

Fig. 5.
